UNITED STATES PATENT OFFICE.

FREDERICK W. COLE, OF NEWTON, MASSACHUSETTS, ASSIGNOR TO GAMEWELL FIRE-ALARM TELEGRAPH COMPANY, OF NEW YORK, N. Y., A CORPORATION OF NEW YORK.

FIRE-ALARM BOX.

1,008,955.

Specification of Letters Patent. Patented Nov. 14, 1911.

Application filed April 25, 1908. Serial No. 429,154.

To all whom it may concern:

Be it known that I, FREDERICK W. COLE, of Newton, county of Middlesex, State of Massachusetts, have invented an Improvement in Fire-Alarm Boxes, of which the following is a specification.

This invention relates to fire-alarm boxes and has for its object to provide the box with a visual indicator, and means operated by the signal-transmitting mechanism for setting said indicator, when the box needs rewinding, as for instance, when one or more alarms have been sent, and means for restoring said indicator when said mechanism is rewound or restored to its normal condition, said indicator being displayed in such manner that a member of the fire patrol or other person going to the box or passing it will readily observe it, and to arrange the visual indicator adjacent the actuating-spring of the signal-transmitting mechanism, whereby it may be operated directly by said spring when the latter expands due to an alarm being sent or to the breaking of the spring, and to provide for restoring the indicator to normal when the signal-transmitting mechanism is rewound, or a new spring is supplied.

Figure 1 is a front elevation of a sufficient portion of a fire alarm box to illustrate my invention, and a visual-indicator embodying my invention, the parts being in their normal positions. Fig. 2 is a modification to be referred to.

Referring to Fig. 1, a well-known form of signal-transmitting mechanism is shown wherein *a* represents the signal-wheel and *b* the actuating-spring. The actuating-spring *b* is normally wound, and when the box is let off, it operates the signal-transmitting train, and while so doing unwinds or expands. This spring is usually wound for quite a number of rounds of the signal, say thirty-six, so that when fully wound a number of alarms may be transmitted, each consisting of say three or four rounds, but it is very desirable to rewind it after one alarm has been transmitted so that it will be kept fully wound. Sometimes the spring breaks and it is very important that notification of such disorder shall be given as soon as possible. Herein I have provided the box with a visual-indicator, which is adapted to visually indicate the fact that an

alarm has been sent or the spring has broken. 55 In the case of the box, at some convenient part thereof, a sight-opening *c* is provided, of any suitable shape and dimensions, and an indicating-plate *c'* is provided, which is movable into and out of position back of 60 said sight-opening.

Referring to Fig. 1 the indicating-plate *c'* is attached to an arm *c²* pivoted at *c³*, and at the lower end of said arm three fingers *c¹¹*, *c¹²*, *c¹³* are provided. The finger *c¹¹* 65 extends over the locking-lever *c¹⁵* of the train and will be engaged by said lever and moved to operate the indicator when said lever is raised, as it will be by means of the actuator *c¹⁶* when operated to send an alarm. 70 The finger *c¹²* extends into proximity to the actuating-spring *b*, so as to be engaged by said actuating spring when the latter expands to thereby indicate the breaking of the spring. The finger *c¹³* engages a spring 75 *c²⁰*, which serves as a means for holding the indicator displayed when the transmitting-mechanism is operated to send an alarm or if the actuating-spring breaks. In this instance the indicator is operated by the signal-transmitting mechanism, the locking-lever thereof being employed as the actuating means and it is also operated by the actuating-spring, two actuating means for the indicator being therefore employed. 80 85

Referring to Fig. 2, the indicating-plate *c'* is attached to an arm *c²* which is pivoted at *c³*, and said arm has a projection *c⁷*, preferably of insulating material, which is arranged adjacent the actuating-spring *b*, so as 90 to be moved by said spring when the latter expands, but said arm is arranged more or less remote from the actuating-spring so that it will not be engaged by it unless the spring breaks, or fully unwinds. An arm *c⁸* 95 is attached to the pivot-shaft *c⁹* which extends into engagement with a cam-disk *c¹⁰* secured to the stop-wheel *c¹¹* of the train and when the transmitting-mechanism is operated said cam-disk is revolved and by 100 turning, lifts the arm *c⁸* and thereby sets the indicator. In this instance it will be observed that the means for operating the indicator for the purpose of setting it to indicate that the transmitting-mechanism 105 needs rewinding is operated through the signal-transmitting-mechanism, the train being employed instead of the actuating-

spring, directly, and that the actuating-spring is only directly employed to operate the indicator to indicate the breaking of said spring. Therefore two actuating means are thus employed for the indicator.

Having thus described my invention, what I claim as new and desire to secure by Letters Patent is:—

1. In a fire alarm box, the combination 10 of signal-transmitting mechanism, a case containing said mechanism having a sight-opening, a visual indicating-plate contained in the case and movable into and out of position back of said sight-opening, a support for 15 said plate having a spring-engaging portion adapted to be engaged by the actuating-spring of the transmitting-mechanism, and also having a portion engaging the trans-

mitting-mechanism, substantially as described.

2. In a fire-alarm box, the combination of 20 signal-transmitting mechanism, a visual indicator at the box, means operated by the transmitting-mechanism for moving said indicator, and means operated by the expansion of the actuating-spring of said transmitting-mechanism for also moving said indicator, substantially as described.

In testimony whereof, I have signed my name to this specification, in the presence 30 of two subscribing witnesses.

FREDERICK W. COLE.
